UNITED STATES PATENT OFFICE

149,729

DESIGN FOR A LAMP

Max Aronek, Altadena, Calif.

Application May 26, 1947, Serial No. 139,277

Term of patent 7 years

(Cl. D48—20)

To all whom it may concern:

Be it known that I, Max Aronek, a citizen of the United States of America, residing at Altadena, in the county of Los Angeles, State of California, have invented a new, original, and ornamental Design for a Lamp, of which the following is a specification, reference being had to the accompanying drawings, forming part thereof.

In the drawings:

Fig. 1 is a front elevational view of the lamp, showing my new design;

Fig. 2 is a side elevational view of the lamp;

Fig. 3 is a side elevational view of the lamp, showing the side of the lamp opposite from the side shown in Fig. 2;

Fig. 4 is a top plan view of the lamp; and

Fig. 5 is a view looking up into one of the lamp globes, taken from line 5—5 of Fig. 3.

I claim:

The ornamental design for a lamp, as shown.

MAX ARONEK.
